ROCK WALL SLICER

James A. Knupke, Corpus Christi, Tex., assignor to Continental Oil Company, Ponca City, Okla., a corporation of Delaware

Filed Feb. 28, 1966, Ser. No. 530,447

9 Claims. (Cl. 175—311)

ABSTRACT OF THE DISCLOSURE

An apparatus for obtaining rock samples from the wall of a well bore wherein the samples are sliced from said wall by converging saw blades and collected in a plurality of sample chambers of said apparatus so as to segregate said samples on the basis of the depth of said apparatus in said well bore.

This invention relates to a tool for obtaining rock samples from the wall of a well bore. More particularly, the invention relates to apparatus for severing a continuous rock slice from the wall of a borehole over a considerable vertical distance, and for collecting and classifying portions of the rock slice.

Data derived from samples of rock obtained from a well bore during a drilling operation are of great value to the geologist in the exploration for oil and gas. Due to changes in the economics of well drilling, and to recent innovations in the apparatus used in this technology, the physical character and the chemical environment of rock samples recovered from wells have been detrimentally altered so as to render it increasingly difficult for the geologist to derive an optimum amount of useful information from such samples.

The present invention provides an improved apparatus for obtaining rock samples from the wall of a well bore over a long interval and in a relatively undisturbed state. Broadly described, the apparatus comprises a housing supporting a pair of saw blades which are mounted in converging planes and have converging cutting edges located outside the housing. The housing contains means for driving the saws in a cutting motion, and a sample receiving compartment disposed below the saw blades, which compartment has a plurality of retractable partition members supported therein in vertically spaced relation. The housing also encloses actuating means drivingly connected to the several retractable partition members for individually and selectively moving these members from a first position, in which they extend across and partition the sample receiving compartment into a plurality of sample chambers, to a second position, in which they are retracted to a non-obstructing position permitting the rock samples to pass freely from the top to the bottom of the compartment. Finally, a gouging protuberance is provided on the outside of the housing directly below the saw blades and adjacent an opening in the wall of the housing which communicates with the sample receiving compartment.

In operating, the rock wall slicer of the invention produces two converging saw cuts in the wall of the well bore adjacent the housing, thus forming a wedge-shape slice of rock which is retained in place after penetration of the saw blades by a narrow neck of rock corresponding in thickness to the distance which separates the saw blades at their points of greatest convergence. As the tool is pulled upwardly in the hole, the gouging protuberance breaks out the slice and directs the broken slices into the sample receiving chamber in the housing. The rock samples thus collected may be segregated or classified in correlation to the depth of the tool by selectively actuating the retractable partition members so that, at different

2

times, the samples are channeled into different chambers within the sample receiving compartment.

An important object of the invention is to provide an improved apparatus for collecting relatively undisturbed samples of rock from a well bore.

An additional object of the invention is to provide a rock wall slicer for collecting slices of rock from the wall of a well bore in a sequence which allows identification of the depth interval from which the slices are cut.

Another object of the invention is to provide an efficient tool for removing slices of rock from the wall of a well borehole over a long interval of the borehole in a relatively continuous operation.

A further object of the invention is to provide a rock wall slicer for use in collecting rock samples from wells, which slicer is relatively economically constructed and is characterized by a long and trouble-free operating life.

In addition to the foregoing described objects and advantages, additional objects and advantages will become apparent as the following detailed description is read in conjunction with the accompanying drawings which illustrate the invention.

In the drawings:

FIGURE 1 is a view in elevation of the rock wall slicer tool of the invention as it appears in a well bore.

FIGURE 2 is a view in elevation of the tool illustrated in FIGURE 1, but showing the tool as it appears when rotated 90° from the FIGURE 1 position.

FIGURE 3 is a vertical sectional view taken through the center of the rock wall slicer tool of the invention.

FIGURE 4 is a horizontal sectional view taken along line 4—4 of FIGURE 1.

FIGURE 5 is an enlarged vertical sectional view of the lower portion of the tool illustrating the manner in which the retractable partition members are utilized to form a plurality of sample chambers for the purpose of segregating the rock samples according to the depth at which they are collected.

Referring now to the drawings, which illustrate an exemplary embodiment of the invention, reference numeral 10 designates a well bore extending downwardly in the earth 12. The rock wall slicer tool of the present invention is designated generally by reference numeral 14, and is shown suspended on a multi-strand wire cable 16 which surrounds and protects a plurality of electrical conduits as hereinafter described. The rock wall slicer tool 14 includes a generally cylindrical housing 18 which is of slightly smaller diameter than the mean diameter of the borehole and is provided with a bottom wall 20 as best illustrated in FIGURE 3.

Mounted on the outside of the housing and spaced approximately 120° in a circumferential direction therearound from each other are a pair of stabilizer elements 22 which can be constructed of spring metal and welded or otherwise suitably secured at each end to the housing 18. The stabilizer springs 22 are each also spaced about 120° around the housing 18 from a pair of elongated, vertically extending slots 24 located in the upper portion of the housing, and provided for the accommodation of a pair of generally circular saw blades 26. Disposed centrally between and below the slots 24 is a sample receiving slot 27 which is positioned immediately over a flared gouging protuberance 28 which is mounted on the outside of the housing 18 and tapered to a sharp point for a purpose hereinafter described. A bracket 30 is located inside the housing 18 and secured to one wall thereof, and a pair of electric motors 32 are mounted on the bracket and are drivingly connected through suitable gearing and shafts to the saw blades 26 in the manner best illustrated in FIGURE 3. As will be noted in referring to FIGURE 3, the saw blades 26 are mounted con-

vergently so as to define an angle of about 60° . The outer portions of the saw blades project through the slots 24, and in a preferred embodiment of the invention, converge to within about $\frac{1}{16}$ -inch of each other.

A sample receiving compartment 36 which, in the illustrated embodiment, takes the form of a large cylindrical shell resting upon the bottom 20 of the housing 18, is positioned inside the housing and below the motors 32 in alignment with the sample receiving slot 27 above the gouging protuberance 28. A plurality of disc-shaped, retractable partitions 38 having a diameter substantially equal to the diameter of the sample receiving compartment 36 are rotatably mounted on shafts 40 which extend diametrically through the compartment 36 and are spaced vertically from each other therein. The retractable partitions 38 are keyed to the shafts 40 which are in turn journaled in the walls of the compartment 36. A plurality of electric motors 42 are drivingly connected to the shafts 40 and are mounted on the side of the compartment 36 between the compartment and the internal wall of the housing 18. Suitable electrical leads 44 and 46 extend from the motors 42 and 32, respectively, upwardly through the wire cables 16 to the surface where they are connected to suitable control switches and a source of electrical power.

OPERATION

For the purpose of obtaining the sample of rock from the wall of the borehole, the rock wall slicing tool 14 is lowered in the borehole 10 to a depth at which it is located slightly below the zones which are to be sampled. The saw blades 26 are then actuated by energizing the motors 32, and the blades cut into the wall of the borehole 10 adjacent the tool 14 in the manner illustrated in FIGURE 4. Preferably, the diametric dimension and the position of the blades 26 are such that each blade cuts into the wall of the borehole to a depth of about one-quarter inch. The narrow slice of rock 50 thus developed is held in place by a small neck at the back thereof which is preferably about $\frac{1}{16}$ -inch in thickness, the distance which separates the saw blades at their point of closest convergence. By permitting the neck to retain the rock slice 50 on the wall until it is gouged out by the gouging protuberance 28, the sample is prevented from falling down in the annulus between the tool and the wall of the borehole.

The rock wall slicing tool 14 is slowly pulled upwardly in the borehole and, as it moves, the saw blades cut in straight lines upwardly in the wall as a result of the housing 18 being forced into abutting contact with the wall of the borehole by the stabilizers 22. The gouging protuberance 28, which is preferably set about $2\frac{1}{2}$ inches below a horizontal line interconnecting the center of the saw blades, breaks out the rock slice formed by the saw blades as the tool moves upwardly in the hole. The slices which are thus gouged out of the wall by the gouging protuberance 28 fall through the slot 27 and into the sample receiving compartment 36.

As the tool 14 moves upwardly in the borehole 10, successively traversing different intervals of the subsurface structure surrounding the borehole, the electric motors 42 are consecutively energized to rotate the retractable portions 38 from the vertically aligned positions shown in FIGURE 3 to the horizontally extending, partitioning positions in which the lowest partition 38 is shown in FIGURE 5. Thus, a plurality of chambers are sequentially established within the sample receiving compartment 36 as the rock wall slicing tool 14 moves upwardly in the hole. Each of the chambers will thus receive and contain slices of rock corresponding to a given interval of borehole traversed by the tool. When the tool 14 has reached the surface, the samples may be removed from the several chambers by actuating the motors 42 in reverse sequence to open up the chambers and, in this

manner, the slices of rock are segregated and classified automatically during the sampling operation. The bottom plate 20 can be made removable by threadedly connecting it to the housing 18 as shown in FIGURES 3 and 4 to further facilitate the removal of the rock slices.

The rock wall slicing device 14 constructed as described can be used for drilling wells in "hard rock" sections. The best results are obtained with the tool in long, indurated sections where the hole is in gauge. The rock wall slicing tool may be run in the hole either during the drilling operation at times following the pulling of the drill bit, or may be employed upon the completion of drilling in the event that very little evaluation is needed during drilling. The tool is simple, compact and relatively inexpensive in its construction, and can efficiently provide relatively undisturbed representative rock samples for geological surveys and data accumulation in all types of well drilling operations.

Although a specific embodiment of the invention has been herein described in order to provide an example to those skilled in the art of the manner in which it is to be constructed, it is to be understood that various innovations and changes can be made in the depicted and described structure without departure from the basic principles which underlie the invention. As an example of a change of this type, the stabilizers 22 mounted on the outer surface of the housing 18 can be made retractable so as to minimize the possibility of sticking the tool in well bores. Also, other arrangements for mounting in the housing 18, the electric motors 32 used to drive the saw blades, could be employed effectively in constructing the rock wall slicing tool. All such changes and modifications which continue to rely on the basic principles herein set forth are deemed to be circumscribed by the spirit and scope 35 of the invention except as the same is necessarily limited by the appended claims or reasonable equivalents thereof.

What is claimed is:

1. A rock wall slicing tool comprising:
a housing having an upper end, a lower end and at least one side wall;

a pair of saw blades supported in said housing and occupying converging planes, said blades having convergent edges located outside said housing and to one side thereof;

means in said housing drivingly connected to said saw blades for actuating said blades;

a gouging protuberance mounted on the side wall of the housing below the convergent edges of the saw blades;

a sample receiving compartment in said housing below said protuberance and communicating with an opening in the side wall of said housing between the protuberance and the convergent edges of the saw blades; and

means in said sample receiving compartment for partitioning said compartment into a plurality of chambers.

2. A rock wall slicing tool as defined in claim 1 wherein said means for actuating said blades comprises an electric motor drivingly connected to each of said blades.

3. A rock wall slicing tool as defined in claim 1 wherein said means for partitioning said compartment comprises: a plurality of retractable partition members each movably mounted in said compartment for movement between partitioning and non-partitioning positions; and

means for individually actuating each of said partition members.

4. A rock wall slicing tool as defined in claim 1 and further characterized to include at least one stabilizer element mounted on the outside of the side wall of said housing on the opposite side of said housing from the convergent edges of said saw blades.

5. A rock wall slicing tool as claimed in claim 1 and further characterized to include a removable bottom plate threaded into the lower end of said housing below said

sample receiving compartment and forming the bottom of said sample receiving compartment.

6. A rock wall slicing tool as claimed in claim 1 wherein said saw blades are circular in configuration and occupy planes which converge at an angle of about 60° to each other. 5

7. A rock wall slicing tool as defined in claim 3 wherein said means for individually actuating each of said partition members comprises an electric motor drivingly connected to each of said partition members. 10

8. A rock wall slicing tool as defined in claim 3 wherein each of said retractable partition members is of disc-shaped configuration and said disc-shaped partition members are mounted for rotation about horizontal axes extending across said compartment and spaced vertically 15 therein.

9. A rock wall slicing tool comprising:
 a generally cylindrical housing having an upper end, a lower end and at least one side wall;
 a pair of circular saw blades supported in said housing 20 and occupying converging planes extending at an angle of about 60° to each other, said blades having convergent edges located outside said housing and to one side thereof;
 motors in said housing drivingly connected to said saw blades for actuating said saw blades upon energization of said motors;
 a cable connected to said housing at the upper end thereof;
 electrical leads to said motors enclosed in said cable; 30
 a gouging protuberance mounted on the side wall of the housing below the convergent edges of the saw blades;
 a generally cylindrical sample receiving compartment of lesser diameter than said housing disposed in said housing below said gouging protuberance and com- 35

municating with an opening in the side wall of said housing between the protuberance and the convergent edges of the saw blades;

a plurality of shafts extending diametrically across said sample receiving compartment and vertically spaced from each other therein;

disc-shaped partition members mounted on each of said shafts for rotation with said shafts about a horizontal axis, said disc-shaped partition members having a diameter substantially equal to the inside diameter of said sample receiving compartment whereby said disc-shaped partition members may be rotated on their respective shafts to positions in which said partition members occupy substantially vertical planes and to positions in which said partition members occupy substantially horizontal planes and thus partition said sample receiving compartment into a plurality of chambers; and
 an electric motor outside said sample receiving compartment and drivingly connected to each of said shafts for individually and selectively actuating each of said partition members to partition said sample receiving compartment and form a plurality of chambers therein.
